CLAIM

The ornamental design for portable information terminal, as shown and described.

DESCRIPTION

1.-5. Portable information terminal

2.1 : Perspective

2.2 : Perspective

2.3 : Perspective view showing changed state

2.4 : Perspective view showing changed state

2.5 : Front

2.6 : Back

2.7 : Right

2.8 : Left

2.9 : Top

2.10 : Bottom

Design 2 is a portable information terminal including: two housings; a flexible display portion which can be folded outward on front surfaces of the two housings; and a camera on a side surface of one of the two housings, as seen in reproduction 2.1 to 2.10.
